United States Patent Office

Des. 201,895
Patented Aug. 10, 1965

201,895

CLOCK

Ellsworth R. Danz, La Salle, Ill., assignor to General Time Corporation, New York, N.Y., a corporation of Delaware

Filed Feb. 19, 1964, Ser. No. 78,701

Term of patent 14 years

(Cl. D42—7)

FIG. 2

FIG. 1

FIG.3

FIG.4

FIG. 1 is a front elevational view of a clock, showing my new design;

FIG. 2 is a side elevational view thereof;

FIG. 3 is a top plan view; and

FIG. 4 is a rear elevational view of the clock.

I claim:

The ornamental design for a clock, substantially as shown.
